Primary Examiner — Cynthia Ramirez*Assistant Examiner* — Llorellys Martinez-Rivera(74) Attorney, Agent, or Firm — Tumey L.L.P.(57) CLAIM

The ornamental design for a bicycle light, as shown and described.

DESCRIPTION

FIG. 1 illustrates a rear view of a bicycle light showing our new design;

FIG. 2 illustrates a front view thereof;

FIG. 3 illustrates a top, front perspective view thereof; and,

FIG. 4 illustrates a side view thereof.

The broken lines shown in FIGS. 1, 3, and 4 illustrate portions of the bicycle light that form no part of the claimed design.
